UNITED STATES PATENT OFFICE.

RUPERT E. RUNDELL, OF ROCKVILLE CENTER, NEW YORK, ASSIGNOR TO INTERNATIONAL CIGAR MACHINERY COMPANY, A CORPORATION OF NEW JERSEY.

SCRAP-BUNCH MACHINE.

Application filed September 25, 1925. Serial No. 58,566.

This invention relates to an improved scrap bunch machine of the type wherein bunches are made of scrap tobacco, to be afterward enclosed within a wrapper to 5 form a cigar.

In scrap bunch machines heretofore commercially used, tobacco feeding means and bunch forming means have been close-coupled so that the feeding means discharges 10 directly into the forming means. While satisfactory results can be attained by these machines when the scrap used is uniform in size, as it usually is when cut for the purpose from the cheaper grades of tobacco, yet in 15 the manufacture of cigars of the higher grades, pieces of scrap are unavoidably produced which differ widely in size, and it is not desirable to cut the larger pieces to make them of the same size as the smaller pieces.

It is preferable that they be used as they are 20 for the reason that the bunch into which they are incorporated will be stronger and will hold its shape better during manufacture and also after transformation into a 25 cigar by the application of a wrapper thereto. The known scrap bunch machines will not successfully handle a mixture of large and small scraps, for the reason that they will not run in the same way in the machine 30 and the latter becomes clogged at a point between the feeding means and the bunch forming means.

The main object of the present invention 35 is the production of a machine that will make satisfactory cigar bunches from a mixture of large and small scrap, and it has been found that this may be accomplished by separating tobacco feeding means and bunch forming means, and introducing, be- 40 tween the two, tobacco forwarding means and coacting mechanism for uniformly re-arranging the tobacco scraps as they move from the feeding means to the bunch forming means. With this and other objects 45 not specifically mentioned in view, the invention consists in certain combinations and constructions which will be hereinafter fully described and then specifically set forth in the claims hereunto appended.

50 In the accompanying drawings, which form a part of this specification and in which like characters of reference indicate the same or like parts, Fig. 1 is a side elevation of a machine constructed in accordance with the invention; Fig. 2 is a front eleva- 55

tion of the machine shown in Fig. 1; Fig. 3 is a plan view of the tobacco re-arranging mechanism; Fig. 4 is a fragmentary view in elevation of a part of the structure shown in Fig. 3; Fig. 5 is an elevation of the feed 60 controlling mechanism and forwarding means drive; Fig. 6 is a fragmentary view of a part of the feed controlling mechanism; and Figs. 7 to 11 inclusive diagrammatically illustrate the action of the mechanism whereby the tobacco is transferred from the forwarding means to the bunch forming means and delivered to the pocket of the chianti belt of the latter.

In carrying the invention into effect, there 70 is provided tobacco feeding means for automatically feeding a mixture of large and small scraps from a mass of the same, relatively distant bunch forming means for making bunches of individual charges of 75 large and small scraps, means for forwarding the tobacco from the feeding means to the forming means, and mechanism coacting with the forwarding means to uniformly re-arrange the tobacco during transit so that 80 when the stream of tobacco reaches the forming mechanism it will be uniform in density with the larger scraps properly positioned among the smaller scraps.

In the best construction contemplated, the 85 feeding means includes a removable hopper having an open bottom discharging directly to the forwarding means, and the hopper has flexible walls which are moved back and forth during the operation of the machine to 90 work the tobacco scraps down through the open bottom of the hopper to the forwarding means; the bunch forming means includes a pusher operating to remove individual charges of scrap from the forwarding means 95 after they have been severed from the forwarded mass, and it also includes a charging plunger and a housing therefor, said housing having a hinged wall acting firstly as a chute to receive a charge from the forward- 100 ing means and direct it to the charging plunger and acting secondly to close the housing ahead of the plunger so that the tobacco cannot become jammed between the plunger and housing wall; the forwarding 105 means includes an intermittently operating belt the operating run of which extends from the feeding means to the bunch forming means and carries the tobacco with it; and said mechanism includes a train of 110

rotating rakers above and spaced from said belt, the function of these rakers being to kick the lumps out of the tobacco stream as it is forwarded, thus re-arranging the same during transit. All of the above mentioned means, mechanism, and parts, may be widely varied in construction within the scope of the claims, for the particular structure selected to illustrate the invention is but one of many possible embodiments of the same. The invention, therefore, is not to be restricted to the precise details of the structure shown and described.

Referring to the drawings: Tobacco scraps, 15 large and small, are fed together into the conical hopper 15, Figs. 1 and 2, which has flexible walls of a suitable fabric. The hopper is provided with a stiffening board 16 on one of its sides, and a similar stiffening 20 board 17 on the other. To the board 16 is secured a plate 18 which is held in position by means of a screw 19 and nut 20. The plate 18 is provided with lugs 21, 21 into which are secured rods 22, 22, passing 25 through lugs 23, 23 of a feed box 24, and held in position by means of set screws 25. By means of this construction, the hopper 15 is made adjustable for height and readily removable for replacement or for discharging at the end of a machine run.

A plate 26 is secured to the board 17 by means of the screw 27 and nut 28, the plate 26 having guide lugs 29 sliding on a horizontal guide rod 30 fastened in a 35 bracket 31 to which are secured rods 32 which pass through lugs 33 on the feed box 24 before referred to. The plate 26 also has a lug 35 to which is pivotally secured a link 36 having hinged connection with a lever 37 fulcrumed at the lug 38 of the feed box support 39. A rocking motion is imparted to the lever 37 which keeps the side of the hopper 15 shaking back and forth to induce a downward movement of the scraps of tobacco therein through the open bottom of the hopper directly on to the belt 40 of the forwarding means which transports the tobacco to the bunch forming means. This belt runs 45 over a pulley 41 mounted in the slotted brackets 42 of the feed box 24, and over a pulley 43 on the shaft 44 rotatably mounted in the bracket 45 which is secured to the support 46 which, like the feed box support 39, is mounted on the table 47 supported by the frames 48 and 49.

As the large and small scraps of tobacco are worked down from the mass in the hopper to the forwarding belt, a continuous 50 stream is formed on the belt, but as they do not run in the same way, this stream is more or less uneven in density and the scraps must be re-arranged to eliminate the unevenness in order that uniform bunches 55 may be made farther along in the machine.

In order that this result may be effected, the stream of scraps is carried along by the belt 40 between channel walls 50 and 51, the belt being prevented from sagging by a horizontal plate 52 secured to supports 70 39 and 46. The mechanism for re-arranging the tobacco stream coacts with the belt 40 so supported. And as the tobacco travels along in the channel it is engaged by a plurality of tandem-S-shaped rakers 53 75 carried by shafts 54, 55, and 56, there being three raking members on each of the shafts 54 and 56, and two raking members on each of the shafts 55, the raking members being mounted on the several shafts in staggered 80 relationship. The rakers engage the top of the stream of tobacco at the various points where it may be too thick, and kick back the surplus into places where it may be too thin, thus re-arranging the tobacco in 85 the stream and making it uniform in density where delivered to the bunch forming mechanism.

The raker shafts pass through the arc-shaped slots 62 of the channel wall 51 and 90 have bearing in the gear box 57, each shaft having mounted on it a spur gear 58 meshing with intermediate gears 59.

The shaft 56 passes through the outer wall of the gear box and, having bearing in the 95 support 60, carries at its extremity beyond the bearing a sprocket 61. The gear box 57 is pivoted on the shaft 56 and may be given any desired inclination by means of a clamp screw 63 locking the slotted bar 100 64 attached to the gear box 57 against the channel wall 51. This brings the rakers from the rear forward progressively nearer or farther away from the belt 40 as may be found compatible with the quantity and consistency of the scrap to be put into the 105 bunches. The tobacco subsequently passes under the smooth roller 65 which is adjustable as to height, as by operation of the adjusting screw 66.

After the tobacco stream has been thus uniformly re-arranged, it passes into the range of action of the knives 67 and 68 which cut it into individual charges in the usual manner.

The parts so far described are actuated as follows (Figs. 1, 2 and 5). To an arm 69 of the lever 37 is pivoted a rod 70 which is also pivoted on a pin 71 of the sprocket 72, which, through the agency of a chain 73, 115 120 actuates the sprocket 61 on the raker shaft 56, thus causing all the rakers to turn in the direction of the arrow. The sprocket 72 is mounted on a shaft 74 having bearing in a bracket 75 and also having mounted on 125 it a sprocket 76 actuating through a chain 77 a sprocket 78 on the shaft 44 of the front belt pulley 43 which drives the forwarding belt 40. On the shaft 74 is also mounted a spur gear 79 meshing with a gear 80 on the 130

shaft 81 carrying the sprocket 82 which, by means of a chain 83 running over an idler 84 mounted on the bracket 75, actuates the sprocket 85 mounted on the shaft 86 of the roller 65 which engages the tobacco stream after it has been re-arranged. The shaft 81 has mounted on it a bevel gear 87 meshing with the gear 88 on the shaft 89 of the intermittent motion device to be described hereinafter. The bracket carries the cross bracket 90 having the idlers 91 and 92 which tighten the chain 77 and 73 respectively. The knives are actuated as follows: The knife 68, sliding between guides 93 and 94, has a pin 95 engaging the slot 96 of a bell crank 97 which is pivotally mounted on a boss 98 of the support 46 and has arms 99 and 100. The arm 99 is pivotally connected to a rod 101 which in turn is pivotally connected to the cam lever 102 mounted on a fulcrum shaft 103 supported in the frames 48 and 49. The lever 102 has a roller 104 in engagement with the cam track 105 of the cam disc 145, being fixedly mounted on the cam shaft 107. The arm 100, by means of the link 108, is movably connected to the arm 109 of the lever 110 mounted on the shaft 111 rotating in the bearing 112 of the support 46. The lever 110 has a slot 113 engaging a pin 114 of the knife 67. The vertical movement of the rod 101, imparted to it by the cam track 105 and operating connections, thus causes the knives to slide in their guides in opposite directions, in the usual manner. At the end of the cutting stroke, the edges of the knives meet and overlap slightly, thus closing the passage and cutting the tobacco stream into individual charges, each sufficient for one bunch.

When the tobacco stream has been cut to separate therefrom an individual charge, all the parts operated by the chain and sprocket transmission are stopped by the intermittent motion device, thus keeping the feeding mechanism stationary while the tobacco is being pushed from the forwarding means to the bunch forming means.

The intermittent motion device (Figs. 5 and 6) has the sprocket 115 fixedly mounted on the sleeve 116 rotatably mounted on the shaft 89 and driven through the chain 117 by the sprocket 118 on the cam shaft 107. A lever 119 is fast on the sleeve 116. This lever carries a pawl 120 provided with a stud 121 on which is mounted a roller 122. A spring 123 keeps the pawl 120 in engagement with a ratchet wheel 124 fast on the shaft 89. The roller 122 periodically engages cams 125 and 126, the cam 126 being fast to a bracket 127 on the support 128, and held by screws 129. The cam 126 is provided with studs 130 protruding through the slots 131 of the cam 125, permitting the angular relation of the two cams to be altered and subsequently fixed by tightening nuts 132 on the studs

130. By changing the angular relation of these cams, the dwell of the roller can be lengthened or shortened. As soon as the roller 122 is lifted by the cams, the pawl 120 is disengaged from the ratchet wheel and consequently the shaft 89 ceases to rotate, thus stopping the forwarding belt, rakers, roller, and the shaking device of the hopper. As soon as the roller has passed over the cams and reaches the gap between the rear end of the track of the cam 126 and the forward end of the track of the cam 125, the spring 123 pulls the pawl down in engagement with the ratchet wheel, and this action is repeated periodically. By diminishing the dwell of the roller on the cams, the period of travel of the forwarding belt is lengthened, thus producing a longer bunch. By increasing the dwell, the reverse occurs.

After the individual charge has been severed from the forwarded stream of tobacco, it is pushed sidewise off the forwarding belt 40 into the range of action of the bunch forming means. This is accomplished by means of a plate 133 (Fig. 2) carrying a roller 134 running over a supporting bracket 135 and over the forwarding belt 40. The plate 133 has an arm 136 pivoted on a pin 137 carried by a bell crank 138, a spring 139 keeping the plate and roller pressing downwardly on the bracket 135 and belt 40. The bell crank 138 is fulcrumed on a pin 140 in a boss 98 of the support 46, and is actuated by means of a rod 141 pivotally connected with a cam lever 142 pivoted on the fulcrum shaft 103 and having a roller 143 engaging with the cam track 144 of the cam 145 on the cam shaft 107.

The plate 133 pushes the charge on to the upper surface of a chute 147 which is hinged on a pin 148 and movable between the plates 149 and having a bracket 150 carrying a roller 151, the spring 152 tending to keep the plate 147 swung outward. The chute 147 is guided in the bracket 153 fastened to the support 46 and has a lug 154 engaging with the roller 151 on its downward stroke which causes the plate 147 to swing forward and close the housing in which the charging plunger 163 operates, so that all the tobacco deposited in the chute will be placed ahead of the plunger before the latter descends.

The housing, formed by the parts 146, 147 and 149, is movable vertically. This is accomplished by means of a link 155 connected to a lever 156 fulcrumed on the boss 98 of the support 46 and connected through the push rod 157 with the bell crank 158 on the fulcrum shaft 103. The bell crank 158 has a roller 159 which is kept in contact, by a spring 160, with the open cam 161 on the cam disc 162 on the cam shaft 107.

Inside of the housing, and guided by it, is a charging plunger 163 having a cigar-shaped recess 164 in its bottom. It is pro-

vided with the plunger rod 165 which slides through the guide bracket 166 secured to the support 46. The top of the plunger rod has a pin 167 engaging a slot 168 in a lever 169 which is pivoted on a boss 170 of the support 46, the lever extension 169^a being actuated by the pushrod 171 connected with the lever 172 mounted on the fulcrum shaft 103 and having a roller 173 kept in engagement with the open cam 174 by means of a spring 175.

Downward movement of the charging plunger 163 within its housing results in depositing the charge in the loop of a chianti belt 176 fastened to the rolling table 177 which, at its outer end is provided with a spring clamp 178 which receives and holds a bunch after formation in the chianti belt. The belt roller 179 (Figs. 1 and 2) is mounted on a bracket 180 of a lever 181 pivotally mounted on a support 182 and having a lug 183 with knuckle joint 184 connected by a rod 187 to the knuckle joint 185 of a lever 186 pivoted on the shaft 188. Oscillating motion is imparted to the lever 186 by means of a lever 189 which carries a roller 190 engaging the track 191 of a cam 192 mounted on the shaft 107, the roller 190 being also mounted on a lever 193 pivoted on the fulcrum shaft 194. The chianti belt 176 is periodically slackened and tightened by means of a rod 195 (Fig. 2) on the bracket 196 of a lever 197 mounted on the fulcrum shaft 194. Pivoted on the lever 197 is the bracket 198 which is adjustable by means of screws 199 and has a roller 200 in engagement with the cam 201 of the disc 145 which imparts a periodical back and forth movement to the rod 195.

Figs. 7 to 11 inclusive illustrate the combined actions of charging plunger and housing. In Fig. 7 the charge is being pushed onto the chute 147, the plunger and housing both being in their highest positions. In Fig. 8 the housing has moved down and is closed with the charge ahead of the plunger which is still in its highest position. The downward movement of the housing has formed the loop in the chianti belt. In Fig. 9 the plunger has moved down, the charge receiving its preliminary shape in the recess of the plunger. In Fig. 10 the housing has moved up, the plunger remaining down, and in Fig. 11 the plunger has moved up, the roller has moved forward and the charge is in process of being rolled into a bunch.

Motive power for the machine is furnished by a motor 202 mounted on the bracket 203, the motor actuating clutch 204 having a sleeve shaft 205 on which is mounted a pinion 206 meshing with a gear 207 on the shaft 208 which, through gears 209 and 210, actuates the camshaft 107 supported in hanger bearings 211 and frame 48. The clutch is periodically thrown out of action

by a lug 212 on the gear 207 engaging a roller 213 on a rod 214 slidably supported in relation with a bracket 218 fastened to the shaft 219 which passes through the sleeve shaft 205 to the clutch levers held in engagement with the clutch disc by a coil spring. When the clutch is disengaged, it can be put into action again by pressing down on the foot lever 220 on the shaft 221 on which is fixedly mounted a lever 222 which is connected by a rod 223 to the tumbling links 216 and 217. This pulls the links down and allows the rod 219 to slide outward through the sleeve shaft and press the clutch levers against the clutch disc.

If it is desired to stop the machine in the middle of a cycle of operation, this can be effected by turning to the left the hand lever 224 mounted on the shaft 225 on which is mounted a cam 226 which engages the bracket 218, which moves the shaft 219 to the left and disengages the clutch. The machine cannot be started while the hand lever 224 is to the left.

For the purposes of trial and adjustment the machine can be turned over by hand by means of a crank 227 on the shaft 228 on which is mounted a bevel gear 229 meshing with another 230 on the sleeve shaft 205.

Generally speaking, the tobacco feeding means and the bunch forming means are well known in the art and a more detailed description of the same is deemed to be unnecessary to a full understanding of the present invention, and in view of this and of the foregoing, a detailed description of the operation of the entire machine is omitted in the interest of brevity.

What is claimed is:

1. A scrap bunch machine comprising tobacco feeding means, relatively distant bunch forming means, means for forwarding tobacco from said feeding means to said forming means, and mechanism coacting with said forwarding means to uniformly re-arrange the tobacco forwarded thereby, said bunch forming means including a charging plunger and a housing therefor, said housing having a hinged wall acting firstly as a chute to receive a charge from said forwarding means and secondly to close said housing ahead of said plunger.

2. A scrap bunching machine comprising tobacco feeding means, relatively distant bunch forming means, means for forwarding tobacco from said feeding means to said forming means, and mechanism coacting with said forwarding means to uniformly re-arrange the tobacco forwarded thereby, said forwarding means including a tobacco-carrying belt, and said mechanism including a train of rotating rakers above and spaced from said belt.

3. A scrap bunch machine comprising tobacco feeding means, relatively distant

bunch forming means, means for forwarding tobacco from said feeding means to said forming means, and mechanism coacting with said forwarding means to uniformly 5 re-arrange the tobacco forwarded thereby, said forwarding means including a tobacco-carrying belt, and said mechanism including a train of rotating rakers above and spaced from said belt, and means supporting said 10 rakers and permitting a change in the spaced relation of said rakers and said belt.

4. A scrap bunch machine comprising tobacco feeding means, relatively distant bunch forming means, means for forwarding tobacco from said feeding means to said forming means, and mechanism coacting with said forwarding means to uniformly 15 re-arrange the tobacco forwarded thereby, said mechanism including a plurality of devices successively acting on the tobacco in 20 said forwarding means.

5. A scrap bunch machine comprising tobacco feeding means, relatively distant bunch forming means, means for forwarding tobacco from said feeding means to said forming means, and mechanism coacting with said forwarding means to uniformly 25 re-arrange the tobacco forwarded thereby, said mechanism including a frame extending 30 along said forwarding means, a plurality of shafts carried by said frame, a plurality

of rakers carried by said shafts, and gearing simultaneously rotating said shafts.

6. A scrap bunch machine comprising tobacco feeding means, relatively distant 35 bunch forming means, means for forwarding tobacco from said feeding means to said forming means, and mechanism coacting with said forwarding means to uniformly 40 re-arrange the tobacco forwarded thereby, said mechanism including a plurality of tandem S-shaped rakers along said forwarding means, and means for rotating said rakers.

7. A scrap bunch machine comprising 45 tobacco feeding means, relatively distant bunch forming means, means for forwarding tobacco from said feeding means to said forming means, and mechanism coacting with said forwarding means to uniformly 50 re-arrange the tobacco forwarded thereby, said mechanism including a plurality of tandem S-shaped rakers along said forwarding means, and means for rotating said rakers, a part of said rakers consisting of 55 an even number of tobacco-engaging members and a part of an uneven number of tobacco-engaging members, said members being arranged in staggered relationship.

In testimony whereof, I have signed my 60 name to this specification.

RUPERT E. RUNDELL.
